**MAKING INDIVIDUAL DRESS PATTERNS
AND FORMS**

Esther Cloward, White Plains, N. Y.

Application December 18, 1952, Serial No. 326,631

15 Claims. (Cl. 33—16)

The present invention relates to an improved foundation structure by means of which a person may make an individually shaped dress pattern or form, and to the finished dress pattern or form, which is especially adapted for intermittent use and storage between times of use.

The advantages to a dressmaker of having a form or pattern accurately sized and shaped to the body of a particular person has long been recognized. Through the use of such a form or pattern, a dressmaker can produce accurately designed and fitted garments, tailor-made to the shape of an individual, without requiring that the individual herself be present for the numerous fittings which are required. To the home dressmaker such a form is almost a necessary prerequisite if she is to make clothes for herself without any outside assistance, since it is impossible for a person to maintain proper posture and at the same time properly fit a garment to her body while that garment is in various stages of completion.

Despite these obvious desirable features, and despite the various suggestions which have been made in the past relative to form making, such forms have not been widely made or used. One reason for this apparently anomalous situation resides in the fact that the making of such dress patterns or forms, closely fitted to the body of a person so as to accurately conform to the contours thereof, has usually required a single continuous forming operation. Once a person starts to make such a form, it has usually been necessary for her to continue with the making of that form until it has been completed. Many hours are involved, and a continuous operation over such a period of time is extremely fatiguing. In the second place, dress forms made according to the prior art have been difficult to remove from the body after they have been shaped, and tend to become distorted during such removal. In the third place, inexpensive forms made according to the prior art tend to become distorted in use, primarily at crucial sizing areas and peripheral edges thereof, such as at the waistline, sides, hipline and neckline. In the fourth place, such dress forms are bulky and present a very real storage problem, particularly to the home dressmaker, who does not usually have available to her sufficient closet or storage space to permit stowing the form in a place where it will be protected against damage or distortion.

The present invention eliminates the above drawbacks and permits the formation of an accurately contoured dress pattern or form in a simple, convenient and inexpensive manner. A foundation or stiffening framework is provided which is universal in nature and can be accommodated to the size and shape of almost any individual. This framework ensures that when the pattern or form has been completed it will be reinforced over critical areas thereof. In addition, and entirely independently of its reinforcing function, the foundation framework is so constructed as to permit removal of the form from the body at any stage of construction of said form without disturbing the adjustment of the framework or the contour of the partially or fully completed form,

2

said framework being readily replaceable on the body whenever desired in the same condition and position that it formerly assumed. As a result construction of an individual dress pattern or form may be carried out in intermittent and piecemeal fashion without detracting from the accuracy of the completed form. This desirable result is achieved by providing the framework with a seam extending generally from top to bottom thereof, the seam edges being secured together by separable fasteners of any desired sort. The framework is initially adjusted to shape and size with the separable fasteners engaged, and that adjustment, once made, remains fixed independently of disengagement of the fasteners, thus permitting the form to be removed from the body whenever desired.

In order to facilitate storage of the dress form, that form is preferably made in a plurality of sections separable from one another and nestable within one another when the form is removed from the body. To this end 20 the framework is provided with a seam extending from side to side thereof, that seam being here shown located at the waistline, the seam edges of the framework, and hence of the finished form, being detachably fastened together by means of separable connectors of any suitable type. The vertical seam separations in the individual sections, previously mentioned with respect to removability of the form from the body between intermittent stages of construction thereof, serve when opened to facilitate nesting of one completed form section within the 30 other for storage purposes without distortion or damage to the form, and also assist in placing an almost completed dress over the form.

As here specifically disclosed, the interior of the completed form is provided with a series of separable connector elements adapted to cooperate with corresponding elements on a pedestal member received inside the form, so that the form may be supported in normal position when in use. It is preferred that the pedestal member itself be collapsible for storage purposes, and it is thus 40 here specifically disclosed.

To the accomplishment of the above, and to such other objects as may hereinafter appear, the present invention relates to the structure of a framework for an individually shaped dress pattern or form and to the structure of a completed sectional dress pattern or form, as defined in 45 the following claims and as described in this specification taken together with the accompanying drawings in which:

Fig. 1 is a front elevational view of the main framework, the various sections of that framework being shown in separated condition;

Fig. 2 is a front elevational view of a supplemental framework section designed for reinforcing the armpit portions of the form;

Fig. 3 is a front elevational view of another supplemental framework section designed to reinforce the neckline of the form;

Fig. 4 is a three-quarter front perspective view illustrating the initial step in the use of the above frameworks in the making of an individual dress form, said step involving the covering of the body with a sheet of gauze 60 or the like;

Fig. 5 is a similar perspective view illustrating the framework of Fig. 1 in position on the body;

Fig. 6 is a similar view but showing the supplemental frameworks of Figs. 2 and 3 in place;

Fig. 7 is a view similar to Fig. 6 but taken partially from the rear of the figure;

Fig. 8 is a view similar to Fig. 6 but showing the form in an initial preliminary stage of completion;

Fig. 9 is a three-quarter front perspective view of the 70 completed form, showing the manner in which it is removed from the body;

Fig. 10 is a perspective view showing the completed form mounted on a pedestal member; and

Fig. 11 is a composite view showing the completed form sections telescoped and the pedestal member disassembled and collapsed for storage.

The main framework element, as shown in Fig. 1, includes a lower part which is formed in two sections 2 and 2' each consisting of a waist-encircling strip 4, a vertical strip 6 and a hip-encircling strip 8, the strips 4 and 8 being secured to opposite ends of the vertical strips 6 so as to extend therefrom in the same general direction and vertically spaced from one another. Each of the strips 4, 6 and 8 is flexible, so as to be accommodatable to the body of the user, but is of an appreciably substantial nature so as to reinforce and strengthen the completed form or pattern. The strips 4 are formed of a sheath 10 of comparatively flimsy material such as kraft paper or the like within which a stiffening strip 12 of cardboard or the like is received. Also received within the sheath 10 is a tape 14 along which conventional separable snap fastener elements 16 are fastened, the sheath being apertured at 18 to permit access to said elements 16. Tabs 20, which may be integral with the sheath 10, extend therefrom inwardly with respect to the framework sections 2 and 2'. The waist-encircling strips 4 together are of a length somewhat less than the normal waist girth expected, and those strips 4 are provided with adjustable length securing means in the form of strings or laces 22 adapted to be tied together so as to cause the waist-encircling strips 4 to snugly encompass the waist of the person whose form is being reproduced. The strings 22 are fastened to the strips 4 somewhat inwardly of the free ends thereof so as to provide greater latitude in the range of waist girths which can be accommodated. For very small waists the ends of the strips 4 may overlap, while for larger waists a gap will exist between the ends of the strips 4, that gap being bridged by the strings 22 (See Fig. 7).

The vertical strips 6 are defined by a sheath 24 within which another tape 14 is received, the tapes 14 on opposite vertical strips 6 having cooperating separable snap fastener elements 16, the sheaths 24 being apertured at 18 so as to permit access to said fastener elements. The sheath 24 is preferably formed of a plurality of layers of kraft paper or the like for adding to its substantiality, and it is preferred that tabs 20 be provided on the strip 6 so as to project inwardly with respect to the framework sections 2 and 2'.

The hip-encircling strips 8, which extend from the vertical strips 6 in the same general direction as and vertically spaced from the waist-encircling strips 4, are rigidified in any convenient manner, as by being formed of a plurality of thicknesses of kraft paper or the like, as was the case with the vertical strip 6, or by being formed as a sheath enclosing a stiffening strip, as was the case with the waist-encircling strips 4. The free ends of the hip-encircling strips 8 are provided with adjustable length securing means such as strings 22', the combined lengths of the hip strips 8 being somewhat less than the normal expected hip girth, engagement of the strings 22' causing the strips 8 to fit snugly about the hips of the wearer in the same manner as was the case with the waist strips 4 previously described.

Cooperable adjustable length securing means, such as the strings 26, are secured to the waist strips 4 and the hip strips 8 respectively and are adapted to engage with one another so as to permit some adjustment of the vertical spacing between said strips 4 and 8 in order to conform to the shape of the body of the user, and so as to ensure that the hip strips 8 are held level with respect to the floor. Tabs 20 extend from the hip strips 8 inwardly with respect to the framework sections 2 and 2', as was the case with the strips 4 and 6.

The framework sections above described permit the construction of a girdle-like dress form or pattern, the contours of which will correspond to the lower portion

of the torso of the wearer, from the waist down. The upper framework part disclosed in the upper half of Fig. 1, either alone or in combination with the supplemental framework shown in Figs. 2 and 3, is used to facilitate construction of a dress form corresponding to the contour of the upper portion of the torso of an individual, from the waist to the neck. The upper framework part shown in the upper half of Fig. 1 is defined by a pair of substantially L-shaped sections generally designated 28 and 28', each of those sections comprising a horizontal strip 30 and a vertical strip 32 connected thereto. The construction of each of the strips 30 and 32 is here shown as similar to that of the vertical strips 6 in the lower framework sections 2 and 2'. The tapes 14 in the horizontal strips 30 carry snap fastener elements 16 adapted to engage with the snap fastener elements 16 carried by the waist strips 4. The tapes 14 carried by the vertical strips 32 carry snap fastener elements 16 cooperating with the elements 16 on the strips 4. Neck-encircling means, in the form of a string or the like 34, is secured to at least one of the vertical strips 32.

Fig. 2 discloses an armseye comprising a curved strip 36 adapted to fit within the armpit of the individual and completely or partially encircle the shoulder, strings 38 or other adjustable length securing devices extending from the ends of the strip 36 and adapted to be secured together on the top of the shoulder of the individual. A rigidifying vertical strip 40 depends centrally from the strip 36. Both strips 36 and 40 are provided with tabs 20 extending away from the shoulder and to both sides of the strip 40. As here specifically disclosed the string 38 passes completely through the strip 36, thus serving in part to rigidify that strip.

The framework part shown in Fig. 3 comprises a neck-encircling strip 42 to the free ends of which adjustable length securing means such as the strings 44 are secured. A rigidifying vertical strip 46 depends from the neck strip 42, and both strips are provided with tabs 20 extending inwardly therefrom with respect to the framework section.

Different rigidifying structures are employed in various of the strips above described. In some cases, as with the strips 4, individual rigidifying strips 12 are employed. In other cases, as with the strips 6, 30 and 32, the tapes 14 which carry the cooperating separable connector elements help to rigidify the strips. The strip 36 is rigidified partially by means of the string 38. Most of the strips are rigidified through the use of a plurality of layers of material adhesively secured together. Clearly other methods of rigidification could be used, and the rigidifying means employed for one strip could be used in any other strip.

To construct a dress form using the frameworks of Figs. 1, 2 and 3, an individual may first cover her body with a sheet 48 of gauze or the like (See Fig. 4), and it is preferred that suitable foundation garments be worn under the gauze 48 in order for the form to correspond to the shape of the individual when she will be wearing a dress. The gauze sheet 48 need not constitute part of the completed dress form and preferably is utilized only for protection of the body during the construction of the dress form.

The next step, as shown in Fig. 5, is to secure the foundation of Fig. 1 in place. The strips 30 are secured to the strips 4, the vertical strips 32 and 6 are secured together, the strips 4 are caused to encircle the waist, the strings 22 are tied so that strips 4 accurately conform to the waist, the alignment of the hip strips 8 is adjusted by means of the strings 26, the hip strips 8 are caused to snugly encircle the hips through engagement of the strings 22', and the vertical strips 32 are held in position centrally of the upper portion of the body by tying the strings 34 around the neck. If only a girdle form is to be constructed, as is usually the case initially, the framework sections 28 and 28' are omitted.

It will be noted that once the strings 22, 22' and 26

have been engaged and adjusted, the framework is accurately fitted to the waist and hips of the wearer. This framework can be removed at any time merely by disengaging the fastener elements 16 on the strips 6, and the framework may be replaced in position at any time by wrapping it around the body and re-engaging the fastener elements 16 and 26, and this without in any way dislocating the adjustment of the strips 4 and 8. In order to assist in resecuring the framework to the body, lacing or strings 50 are provided on the strips 4 and near the strips 6. Knotting and pulling those strings together will cause the vertical strips 6 to approach one another and thus facilitate engagement of the fastener elements 16 on opposed strips 6.

As may be seen in Fig. 8, the form itself is constructed by pasting a series of small strips 51 of kraft paper or the like to one another and to the frame work strips in a progressively overlapping manner. The tabs 20 on the various strips facilitate this procedure. In order to produce a form of sufficient rigidity, several thicknesses of strips 51 should be employed. It will be noted that it is not necessary to cover the strips 4, 6 and 8 themselves except along their edges and over any gaps between the free ends of the strips 4 and 8 respectively which may occur at the back of the individual.

Since the overlapping paper strips 51 are secured primarily to one another and to the framework strips, and may readily be separated from the gauze sheet 48, it is possible to remove the framework with the overlapping strips 51 attached no matter in what stage of completion the dress form may be, and without adversely affecting the adjustment of the framework and the conformity of the overlapping strips 51 to the particular contours of the body.

The form for the upper portion of the body is similarly constructed. It may be constructed entirely independently of the lower girdle-like form or pattern if desired, but will be here described as made at the same time as said lower form. The framework sections 28 and 28', with the strips 32 secured to one another, is first placed in position by engaging the strips 30 with the strips 4 and by tying the strings 34 around the neck. The armscye strips 36 are placed in position by tying the strings 38 over the shoulder. The neck-encircling strip 42 is tied in front by means of the strings 44, the strip 46 extending down the back of the wearer. The body of the form itself is constructed by using a plurality of layers of overlapping and adhesively connected strips 51, as was the case with the girdle section.

When the form has been entirely completed, that is to say, when the body of the wearer has been entirely covered with the overlapping paper strips 51, the form is removed from the body. This can be done merely by separating the vertical strips 32 and 6 and removing the form as though it were a coat, stripping it from the gauze sheet 48. When, as specifically shown in Fig. 9, the form includes shoulder caps, the front portions of the upper section of the form should be slit at 52 in order to facilitate removal of the upper section of the form without distortion thereof, that slit 52 extending from one armpit across the upper portion of the body to the strip 32 and then upwardly to the neck alongside the strip 32 and through the strip 42. After the completed form has been removed, this slit 52 is recovered by overlapping strips of paper (See Fig. 10). Thereafter the inside of the form is covered with one or more layers of overlapping adhesively secured strips 51, this further rigidifying the form and also covering the exposed adhesived surfaces of the previously applied strips 51.

Not only is the completed form removable from the body, but the form itself is readily separable into upper and lower sections, this being accomplished by separating the fasteners 16 carried respectively by the strips 4 and 30 and by cutting whatever portion of the overlapped paper strips 51 may be necessary at the rear of the form

where the ends of the strips 4 and 30 do not meet. The two form sections, to wit, a girdle section generally designated 54 and an upper torso section generally designated 56, may be stored in nested condition, as shown in Fig. 11, thus taking up but a minimal amount of space. Nesting of the two sections may be facilitated by opening the vertical seam in the upper section 56 defined by the strips 32, and then slightly rolling the upper section 56 to permit it to be received inside the lower section 54.

The completed dress form will, through the framework originally employed in its construction, be well rigidified at crucial areas thereof and consequently will retain its shape and resist abuse. The girdle-like lower section 54 will be reinforced along practically all of its upper and lower edges by means of strips 4 and 8 respectively, and will be reinforced down the front middle, where it is separable, by the vertical strips 6. The upper section 56 of the form will be strengthened and protected at its lower edge by the strips 30, at the neck by the strip 42, and at the armpits by the strips 36. A substantial portion of the rear center of the upper form section 56 will be rigidified by the strip 46, and the strips 40 will reinforce the upper form section 56 over a substantial length and area between the armpits and the waist. In addition, the strips 32 will reinforce substantially the entire front center of the form section 56 along its separable seam edges.

In order to mount the form in a convenient manner, the inside of the girdle section 54, at a point below the waistline, is provided with a series of separable snap fasteners 58, held in place, for example, by sewing a tape carrying such elements on the inner surface of the girdle form 58. The pedestal member on which the form is mounted is here disclosed as comprising a cardboard tube 60 having cooperating separable fastener elements 62 at the top thereof and having holes 64 at the bottom thereof through which strings 66 on a base plate 68 are adapted to be passed. The free edges of the tube 60 are provided with detachable fastening elements 70 so that the tube may be rolled up into a small space for storage, as viewed in Fig. 11, or expanded to tubular shape for supporting purposes, as shown in Fig. 10, and held in expanded tubular shape by engagement between the fastener elements 70.

The advantages of the framework and dress form structure of the present invention insofar as ease of adjustment, removability and replacement of the form during construction and storage of the completed form are concerned, have been set forth above. It may be here further noted, however, that the vertical seam in the form as defined by the vertical strips 32 facilitates use of the form with dresses which are almost completed. Such dresses may be placed over the form without distorting the dress or the form by unsnapping the strips 32, contracting the shoulders of the form, passing the dress over the form in its contracted condition, and then resecuring the strips 32 to one another.

While conventional snap fasteners have been here disclosed as incorporated into the framework of the form of the present invention, it will be apparent that any type of separable fastener, such as hooks and eyes, slide fasteners and the like, could be employed. While this specification relates specifically to the production of forms or patterns simulating the configuration of a human torso, it will be apparent that the invention in its broader aspects has to do with the simulation of other body parts, such as the head, and the simulation of objects other than human bodies. While but a single embodiment of the present invention has been here specifically disclosed, it will be apparent that many variations may be made in the details thereof without departing from the spirit of the invention as defined in the following claims.

I claim:

1. A universal framework for an individually shaped dress form comprising a two-piece waist-encircling strip, a pair of vertical strips depending from adjacent ends of

said pieces, and a two-piece hip-encircling strip, each of said hip-strip pieces extending from one of said vertical strips in the same general direction as and vertically spaced from said waist-strip pieces, adjustable length securing means at the free ends of said waist-strip and hip-strip pieces for adjustably securing together the free ends of said respective strips so as to cause them to snugly encircle the waist and hips respectively of a body, and separable securing devices along said vertical strips, whereby said framework, in two sections each defined by a vertical strip with attached waist- and hip-strip pieces, may be releasably secured in place around the body and removed therefrom without altering the setting of said adjustable length securing means.

2. In the framework of claim 1, cooperable adjustable length securing means fastened to a waist-strip piece and an opposed hip-strip piece, whereby the vertical spacing between said strips may be adjusted.

3. In the framework of claim 1, cooperable tensioning devices at opposed points on said vertical strips, whereby said strips may be drawn together about a body so as to facilitate engagement of said separable securing devices.

4. In the framework of claim 1, tabs spaced along the length of said strips and projecting inwardly with respect to said framework sections, so as to facilitate the adhesive attachment thereto of the body of said dress form.

5. The framework of claim 1, in which said strips comprise a sheath of comparatively flimsy material to which the dress form body may be adhesively secured, and a stiffening element of more substantial material in said sheath.

6. The framework of claim 1, in which at least one of said strips comprises a sheath of comparatively flimsy material to which the dress form body may be adhesively secured, a stiffening element in said sheath, and a tape also in said sheath and carrying said separable securing devices, said sheath being apertured to permit access to said separable securing devices.

7. In combination with the framework of claim 1, an additional framework defined by a pair of substantially L-shaped members each comprising a horizontal and a vertical strip, neck-encircling means secured to at least one of said vertical strips, separable cooperating securing devices along said vertical strips, and separable cooperating securing devices along said horizontal strips and the waist-strip pieces of the framework of claim 1.

8. In combination with the composite framework of claim 7, a supplemental framework defined by a neck-encircling strip having adjustable length securing means at the ends thereof for adjustably securing together said ends as said strip encircles a neck.

9. In combination with the composite framework of claim 7, a supplemental framework defined by a neck-encircling strip having adjustable length securing means at the ends thereof for adjustably securing together said ends as said strip encircles a neck, and a vertical strip depending from said neck-encircling strip and adapted to extend down the back of a body when said neck-encircling strip is secured in place.

10. In combination with the composite framework of claim 7, supplemental framework defined by a pair of armpit-encircling strips having adjustable length securing means at the ends thereof for adjustably securing together said ends as said strip encircles an armpit and shoulder.

11. In combination with the composite framework of claim 7, supplemental framework defined by a pair of

armpit-encircling strips having adjustable length securing means at the ends thereof for adjustably securing together said ends as said strip encircles an armpit and shoulder, and a vertical strip depending from said armpit-encircling strip and adapted to extend from said armpit toward the waist of a body.

12. A universal framework for an individually shaped dress form comprising a two-piece waist-encircling strip, a pair of vertical strips depending from adjacent ends of said waist-strip pieces, adjustable length securing means at the free ends of said waist-strip pieces for adjustably securing together their free ends so as to cause said strip to snugly encircle the waist of a body, and separable securing devices along said vertical strips, whereby said

15 framework, in two sections each defined by a vertical piece and attached strip piece, may be releasably secured in place around the body and removed therefrom without altering the setting of said adjustable length securing means.

20 13. The framework of claim 12, in which at least one of said strips comprises a sheath of comparatively flimsy material to which the dress form body may be adhesively secured, a stiffening element of more substantial material in said sheath, and a tape also in said sheath and carrying

25 said separable securing devices, said sheath being apertured to permit access to said separable securing devices.

14. In combination with the framework of claim 12, an additional framework defined by a pair of substantially

30 L-shaped members each comprising a horizontal and a vertical strip, neck-encircling means secured to at least one of said vertical strips, separable cooperating securing devices along said vertical strips, and separable cooperating securing devices along said horizontal strips and the waist-strip pieces of the framework of claim 12, and a supplemental framework defined by a neck-encircling strip having adjustable length securing means at the ends thereof for adjustably securing together said ends as said strip encircles a neck.

35 15. In combination with the framework of claim 12, an additional framework defined by a pair of substantially L-shaped members each comprising a horizontal and a vertical strip, neck-encircling means secured to at least one of said vertical strips, separable cooperating securing

40 devices along said vertical strips, and separable cooperating securing devices along said horizontal strips and the waist-strip pieces of the framework of claim 12, and supplemental framework defined by a pair of armpit-encircling strips having adjustable length securing means at the ends thereof for adjustably securing together said ends as said strip encircles an armpit and shoulder.
